COMBINATION BOAT AND CAMPING TRAILER

Donald J. Clow, 640 Oak St., Laguna Beach, Calif.

Filed July 25, 1960, Ser. No. 61,502

Term of patent 14 years

(Cl. D14—3)

The side not shown is a mirror image of the side shown.

I claim:

The ornamental design for a combination boat and camping trailer, substantially as shown and described. -
